(57) **CLAIM**

The ornamental design for a wrist display, as shown and described.

DESCRIPTION

FIG. 1 is a top, right side perspective view of a wrist display showing our new design;

FIG. 2 is a bottom right side perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a rear elevational view thereof; and,

FIG. 8 is a front elevational view thereof.

The structural features depicted by broken lines have been shown for the purpose of illustrating portions of the wrist display that form no part of the claimed design.
